CIGAR WRAPPING MECHANISM

Birger Hellström, Karlsudd, Vaxholm, Sweden,
assignor to Aktiebolaget Formator, Stockholm,
Sweden, a joint-stock company of Sweden

Application June 13, 1939, Serial No. 278,951
In Sweden June 14, 1938

5 Claims. (Cl. 131—36)

This invention relates to improvements in cigar wrapping mechanisms.

In cigar wrapping mechanisms antifriction means have been provided whereby the flag of the wrapper is controlled after it has been released from the wrapper support and before it is completely wound about the head of a cigar bunch, and it is an object of the present invention to still further improve said improvement.

In the drawings,

Fig. 1 is a perspective view, partly broken away, of a cigar wrapper mechanism according to this invention, several parts being omitted in the interest of clarity;

Fig. 2 is an end view, partly broken away, of the mechanism of Fig. 1;

Fig. 3 is an enlarged longitudinal sectional view of an embodiment of the invention; and

Fig. 4 is an enlarged sectional view taken on the line IV—IV of Fig. 3.

Referring to the drawings, the cigar bunch 1 is introduced between the revolving bunch rollers 7. The cigar wrapper is conveyed to the cigar bunch by a suction carrier 8 which is movable crosswise over the bunch rollers 7 and a wrapper tension plate 3 which is movable periodically towards the bunch rollers 7 into its foremost position as shown in Figs. 1 and 2. For the latter purpose a bell crank lever 12 is pivoted on a pin 13 in the frame 14 and actuated by a spring 18 so that its roller 15 rides upon a cam 16 which is secured to the revolving shaft 17. A drum 10 for conveying the wrapper flag 4 is associated with the tension plate 3. Thus the drum 10 is rotatably journaled on a sleeve 31, which is introduced into an arm 11 which is pivoted at 19 to the tension plate. After the arm 11 has been swung upwards the drum 10 can be pulled off the sleeve 31 and be cleaned, or the sleeve 31 can be removed together with the drum 10 from the arm 11. The drum 10 has perforations 30 in its side wall. The sleeve 31 has an upper longitudinal slot 54 and a tubular extension 9 which is adapted to register periodically with an opening 73 of a suction chamber 32 which is secured to the frame 14. The slot 54 extends peripherally about 35° and it is positioned so that any perforation 30 of the revolving surface of the drum 10 is subjected to suction about 5° before it reaches its uppermost position. At every time when the tension plate 3 is advanced into the position shown in Figs. 1 and 2 the extension 9 of the spindle 31 will register with the opening 73 of the suction chamber 32 so that suction is established within the sleeve

31. Thereby only those perforations 31 of the drum 10 which communicate with the slot 54, and consequently only the upper part of the drum 10, are subjected to suction effect. 5 In operation, the wrapper is moved by the wrapper carrier 8 in the direction of the arrow, and shortly before it reaches the position shown in Fig. 2 the nicked flag 4 of the wrapper is transferred to the drum 10 which is rotated under the pulling action of the revolving bunch 1 and the wrapper 2 or under frictional action caused by the bottom surface of the wrapper carrier 8. By the suction action of the upper part of the drum 10 the nicked wrapper flag 4 15 will be transferred safely from the wrapper carrier 8 to the drum 10 and even though the suction surface of the wrapper carrier 8 would be coated with paste. Thus any risk of splitting the nicked wrapper flag will be obviated. The 20 wrapper flag adheres to the sucking upper part of the drum 10 above the slot 54 but is released as soon as it leaves said upper part. When the wrapper flag has left the carrier drum 10 and been supplied to the bunch head the wrapper 25 carrier 3 is retracted whereby communication between the sleeve 31 and the suction chamber 32 is interrupted.

I claim:

1. In a cigar wrapping mechanism, a wrapper 30 delivery means, and air suction means operative to successively remove the wrapper flag from said wrapper delivery means and transfer said flag to the head of a bunch positioned in said wrapping mechanism.

35 2. In a cigar wrapping mechanism, a wrapper per delivery means, a suction source, and a hollow perforated anti-friction carrier to be connected interiorly to said suction source to successively remove the wrapper flag from said 40 wrapper delivery means and transfer said flag to the head of a bunch positioned in said wrapping mechanism.

3. In a cigar wrapping mechanism, a wrapper delivery means, a suction source, and a rotatable hollow roller to be connected with said suction source, said roller having a perforated cylindrical suction surface to successively remove the wrapper flag from said delivery means and transfer said flag to the head of a bunch positioned in said wrapping mechanism.

45 4. In a cigar wrapping mechanism, a wrapper delivery means, a suction source, a rotatable hollow roller for connection with said suction source, said roller having a perforated cylindrical suction surface for successively removing

the wrapper flag from said delivery means and transferring said flag to the head of a bunch positioned in said wrapping mechanism, and a hollow spindle, said hollow roller being mounted on and encompassing said spindle, said spindle being interiorly connected to said suction source and having a longitudinal slot for communicating suction to part of the suction surface of the roller mounted thereon.

5. In a cigar wrapping mechanism, a wrapper tension plate, a suction carrier movably mounted on said plate for conveying the wrapper flag to the head of a bunch positioned in said wrapping mechanism.

BIRGER HELLSTRÖM.
